MACHINE FOR PACKING EGGS

Harold J. Mumma, Riverside, Calif., assignor to Food Machinery and Chemical Corporation, San Jose, Calif., a corporation of Delaware

Filed Dec. 20, 1954, Ser. No. 476,128

6 Claims. (Cl. 221—210)

The present invention relates to machines for packing eggs. More particularly the present invention relates to machines for packing eggs into containers that provide several parallel rows of pockets each adapted to receive an individual egg with its main axis disposed vertically. Containers of this type are usually made from papier-mache and are generally known under the name "filler." When filled with eggs, they are stacked in superposed tiers within boxes, crates or cases for shipping to distributors and retailers.

It is an object of the present invention to provide a machine that is operable to fill the individual pockets of a filler with eggs.

Another object is to provide a machine, of the type referred to, that is of simple construction yet dependable in operation.

Another object is to provide mechanism, in a magazine adapted to receive a stack of superposed fillers, that is dependably operable to discharge the fillers individually from the magazine onto a conveyor underneath.

Another object is to provide mechanism, in a magazine adapted to receive a stack of superposed fillers, that is operable to separate the fillers of the stack and to discharge them individually from the magazine onto a filler supply conveyor underneath.

Another object is to provide a magazine that is adapted to receive a stack of superposed fillers and which is operable to positively deliver the lowest filler in the stack onto a conveyor underneath while dependably retaining the remaining fillers in the stack within the magazine.

Another object is to provide a machine, of the type referred to, that is operable to successively place the consecutive pocket rows of a filler delivered thereto into egg receiving position relative to the egg supply conveyor.

Another object is to provide a machine to which a stack of fillers is delivered and past which a procession of eggs may be conducted on a suitable conveyor and which is operable to separate the fillers from each other and place them with their pocket rows successively into egg receiving position below the conveyor so that the eggs may be dropped from the conveyor into the individual pockets of the fillers.

Another object is to provide a simple yet dependably operating conveyor for fillers.

These and other objects of the present invention will become apparent from the following description of the accompanying drawings, which illustrate a preferred embodiment thereof, and wherein:

FIG. 1 is a side elevation of an egg packing machine embodying my invention.

FIG. 2 is an end elevation of the egg packing machine illustrated in FIG. 1.

FIG. 3 is a longitudinal section through the egg packing machine taken along line 3—3 of FIG. 2 and viewed in the direction of the arrows associated with said line.

FIGS. 4, 5, 6 and 7 are fragmentary longitudinal sections through the egg packing machine taken along lines 4—4, 5—5, 6—6, and 7—7, respectively, of FIG. 2.

FIG. 8 is a fragmentary perspective of the magazine of the egg packing machine illustrated in FIG. 1 and of the power trains for the various movable components of said magazine.

FIG. 9 is an elevational detail view, partly in section,

2

of a clutch that is interposed in the power train of the filler supply conveyor comprised in the egg packing machine illustrated in FIG. 1.

FIG. 10 is an exploded fragmentary perspective of the clutch illustrated in FIG. 9.

FIG. 11 is a side elevational detail view of component mechanisms of said clutch.

FIG. 12 is a perspective of a filler of the type served by the egg packing machine of the invention.

FIGS. 13, 14 and 15 are fragmentary, end elevational detail views, largely in section, illustrating three consecutive stages in the operation of a mechanism for separating the individual fillers of a stack of fillers that has been placed into the filler magazine of the egg packing machine.

FIGS. 16, 17, 18, 19 and 20 are fragmentary, end elevational detail views, partly in section, of mechanism for dispensing fillers from the magazine of the egg packing machine, illustrating a sequence of consecutive operational positions of said mechanism.

FIGS. 21, 22 and 23 are fragmentary perspectives illustrating three consecutive operational positions of the filler dispensing mechanism shown in FIGS. 16 to 20.

FIGS. 24 and 25 are vertical sections, similar to FIGS. 16 to 20 illustrating details of the same filler dispensing mechanism.

FIG. 26 is a perspective detail view illustrating a component in one of the power trains of the filler dispensing mechanism.

FIG. 27 is a fragmentary perspective illustrating a portion of the egg supply conveyor for the egg packing machine illustrated in FIG. 1.

FIG. 28 is a perspective detail view illustrating one of the egg supporting buckets of the egg supply conveyor shown in FIG. 27.

FIG. 29 is a perspective view of control mechanism for the egg supply conveyor which operates to release eggs from the buckets of said egg supply conveyor at the proper time as they pass over a filler underneath.

FIG. 30 is a plan view, partly in section, of the control mechanism illustrated in FIG. 29.

FIG. 31 is a fragmentary side elevational detail view, partly in section, of one of the components of the control mechanism illustrated in FIGS. 29 and 30.

FIGS. 32 to 39, are diagrammatic plan views of the control mechanism illustrated in FIGS. 29 and 30, showing a sequence of consecutive operational positions thereof.

FIG. 40 is the electric circuit diagram of the egg packing machine of the invention.

FIGS. 41, 42, 43, 44 and 45 are fragmentary, diagrammatic perspectives of the egg packing machine illustrated in FIG. 1 showing a sequence of different operational positions thereof.

General construction of the machine

The egg packing machine of the invention comprises a horizontally extending continuously advancing conveyor 100 that carries the eggs to be packed in single file line to the actual packing station (FIGS. 1, and 41 to 45). It also comprises an intermittently operating filler supply conveyor 102 that extends below and at right angles to the egg supply conveyor at the actual packing station, and a filler magazine 104 that is disposed above said filler supply conveyor at a point in front of the egg supply conveyor and which is adapted to receive a stack of fillers F and is operable to drop them individually onto the filler supply conveyor 102 for conveyance thereon into egg receiving position below the egg supply conveyor 100.

With the aid of a control mechanism 105 the operation of the three component mechanisms 100, 102 and 104 is regulated in such a

manner that above a filler positioned on filler supply conveyor 102, the egg supply conveyor 100 drops a number of eggs equal to the number of pockets comprised in each pocket row of the filler at points displaced in a direction longitudinally of the egg supply conveyor advance by a distance equal to the distance between the center points of the pockets in each filler pocket row, commencing from the downstream side of the filler relative to the advance of the egg supply conveyor. Thereupon, the filler supply conveyor 102 is actuated to advance by a distance effective to place the directly succeeding pocket row of the filler into egg receiving position below the egg supply conveyor, whereupon the egg supply conveyor is again caused to drop a number of eggs equal to the number of pockets comprised in each filler row at longitudinally displaced points in upstream direction commencing from the downstream side of the filler; and at appropriate intervals corresponding to a number of advances of said filler supply conveyor equal to the number of pocket rows comprised in the processed fillers, the filler magazine 104 is actuated to drop an individual filler onto the filler supply conveyor 102.

The filler supply conveyor

The filler supply conveyor 102 comprises an endless sprocket chain 106 (FIG. 3) trained around a trailing sprocket 108 and a leading sprocket 110. The trailing sprocket 108 is the drive sprocket of the conveyor and is firmly mounted upon a transverse shaft 112 that is rotatably supported in a pair of vertically disposed transversely spaced side panels 114a and 114b which form part of the conveyor frame 115 and whose bottom edges are turned inwardly to form base flanges 116a and 116b that may be rigidly connected by suitable cross channels 118 and 119 to impart sturdiness to the structure (FIG. 2). The leading sprocket 110 is an idler sprocket and is rotatably mounted upon a transverse shaft 120 which is adjustably supported in another pair of transversely spaced vertically disposed side panels 122a and 122b whose bottom edges are likewise turned inwardly to form base flanges 124a and 124b, respectively, which are connected by a cross bar 125. Rigidly supported on and projecting outwardly from the endless chain 106 are pairs of conically shaped impeller members 126 (FIG. 3).

Egg holding fillers, of the type mentioned hereinbefore, are usually molded from papier mache and exhibit on their underside conical cavities or recesses 130 corresponding to the conical protrusions 132 on their upper side which define the egg supporting pockets 134 (FIG. 12). The conical impeller members 126 are arranged to engage the foremost center cavity and the rearmost center cavity of the fillers as illustrated in FIG. 12, and the fillers slide upon pairs of longitudinally extending bars 136a, 136b and 138a, 138b that are disposed at either side of the upper run 140 of the conveyor chain 106. Said bars are mounted upon a base plate 142 of U-shaped cross section that rests upon the side panels 114a and 114b of the conveyor frame 115, and they extend all the way to the leading end of the conveyor where they are suitably supported from the beforementioned side panels 122a and 122b. Likewise supported from the side panels 114a, 114b and 122a, 122b is a guide bar 144, which lends support to the upper run 140 of the sprocket chain 106. The arrangement is such that the upper run 140 of the conveyor chain 106 extends along the central longitudinal groove on the under side of the filler, while the two supporting bars 136a, 138a and 136b, 138b at either side of chain 106 engage two longitudinal grooves of the filler on either side of its central groove.

To operate the filler supply conveyor, rotary power from a motor (not shown) which operates continuously during the performance of the machine, is applied to a sprocket 146 that is firmly mounted upon the laterally projecting end of a sleeve 148 which turns upon the drive

shaft 112 of the conveyor (FIGS. 2 and 9). Interposed between the sleeve 148 and the conveyor drive shaft 112 is a clutch 150 that is normally held in disengaged condition so that the filler supply conveyor 102 remains at rest, and which is briefly engaged whenever it is necessary to advance the filler supply conveyor to place a new pocket row of a filler thereon into egg receiving position relative to the egg supply conveyor 100.

Having reference to FIGS. 9 and 10, the sleeve 148 forms a radially enlarged head 152 around which is wound a coil spring 154. The trailing end of said spring (viewed in the direction of rotation of sleeve 148) is anchored in a disc 156 that is firmly mounted upon the conveyor drive shaft 112, while its leading end is anchored in a ratchet 158 that is rotatably supported upon the sleeve 148 by means of a ball bearing 160. Normally the ratchet 158 is held against rotation by means of a latching pawl 162 that is rotatably mounted upon a stub shaft 164 (FIG. 9) which projects from the inner surface of the side panel 114b, the nose 166 of said pawl being forced into engagement with one of the teeth of the ratchet 158 by means of a strong spring 168 (FIGS. 2 and 11). As long as the leading end of the hereinbefore mentioned spring 154 around sleeve head 152 is positively restrained from movement in the direction of rotation of sleeve 148 by its connection with the ratchet 158 in latched condition, while frictional engagement of said spring 154 with the head 152 of rotating sleeve 148 endeavors to impart rotation to said spring 154, the spring 154 is subjected to an unwinding stress which increases its diameter so that its turns lose contact with the head 152 of sleeve 148. As a result thereof, the sleeve 148 idles ineffectively within the spring 154 and the drive shaft 112 of filler supply conveyor 102 remains at rest.

However, whenever the pawl 162 is disengaged from the ratchet 158, the clutch spring 154 may contract to its normal diameter and grip the head 152 of sleeve 148; and as the spring 154 tends to turn with the sleeve 148 while its trailing end is held back by the inertia of the conveyor mechanism in whose disc 156 it is anchored as explained hereinbefore, said spring 154 is subjected to a winding strain which reduces its diameter so that it clutches firmly the head 152 of rotating sleeve 148 and participates fully in the rotary movement thereof forcing the conveyor drive shaft 112 to follow suit. When rotation of the ratchet 158 is blocked by re-engagement of the pawl 162 with a subsequent one of the ratchet teeth, the spring 154 is again subjected to an unwinding stress which interrupts the driving connection between the sleeve 148 and the conveyor drive shaft 112, and the conveyor comes to a halt. To prevent the conveyor 102 from overshooting its mark under its momentum when further rotation of the ratchet 158 is blocked by the pawl 162, the disc 156 is provided with an adjustable stop member 157 that is arranged to strike against a stop ledge 159 which is rigidly secured to and projects laterally from the ratchet 158 (FIGS. 9 and 10).

To disengage the pawl 162 from the ratchet 158 for the purpose of allowing the filler supply conveyor 102 to advance, a solenoid 170 (FIGS. 2 and 11) is arranged below said pawl 162. The normally projected armature 172 of said solenoid 170 is pivotally connected through a link 174 to the free end of pawl 162. Thus, whenever the solenoid 170 is energized and retracts its armature 172, it withdraws the nose of the pawl 162 from the ratchet 158 causing engagement of the clutch 150 in the manner described hereinbefore.

If the fillers form five consecutive pocket rows as illustrated in FIG. 12, the filler supply conveyor 102 must be arranged to advance four times by the relatively short distance that is necessary to place a directly succeeding pocket row into egg receiving position below the egg supply conveyor 100; and after the last pocket row of a particular filler has been filled with eggs, the filler supply

conveyor 102 must advance by a distance appropriate to place a succeeding filler with its leading pocket row into egg receiving position relative to said egg supply conveyor. Accordingly, the peripheral edge of the ratchet 158 is divided into four teeth 176, 178, 180 and 182, respectively, that have relatively short backs corresponding to the short conveyor advances necessary to place a directly succeeding pocket row into egg receiving position, and a fifth tooth 184 having an elongated back corresponding to the conveyor advance necessary to place the first pocket row of a succeeding filler into egg receiving position relative to the egg supply conveyor 100.

Energization of the pawl retracting solenoid is controlled from the hereinbefore mentioned central control mechanism 105 that governs the release of eggs from the egg supply conveyor as well as the advance of the filler supply conveyor in a manner to be described in greater detail hereinafter.

The magazine

Disposed above the filler supply conveyor 102 ahead of the egg supply conveyor 100 is the magazine 104 which is of a rectangular horizontal cross section and is of a size appropriate to receive a stack of vertically superposed fillers. The magazine 104 has two vertically disposed side walls 186a and 186b, respectively, which have outwardly flared upper edges 188a and 188b, respectively, and which are suitably supported from the outer side walls 190a and 190b of the U-shaped base plate 142 that carries the hereinbefore mentioned filler supporting bars 136a, 136b and 138a and 138b. The magazine 104 has also a rear wall 192 which has an outwardly flared upper edge 194 and which is suitably supported from the magazine side walls 186a and 186b. Said rear wall 192 may be provided with an observation and manipulation aperture 196 in the form of an inverted arch. Additionally the magazine comprises a front wall 198 that has also an outwardly flared upper edge 200, is likewise supported from the side walls of the magazine and terminates at the bottom, a distance above the supporting bars 136a, 136b, 138a and 138b of the filler supply conveyor 102 to permit a filler sliding on said bars to emerge freely from the magazine as shown in FIGS. 1 and 3. The magazine front wall 198 may also be provided with an observation and manipulation aperture 202 which has preferably the form of an upright arch as best shown in FIGS. 2 and 8.

Filler dispensing mechanism

Provided adjacent the side walls of the magazine and operating through suitable apertures or windows 204a, 204b, 204c and 204d near the lower ends thereof (FIGS. 1 and 3) is a mechanism 208 that is normally effective to maintain a stack of fillers within the magazine 104 above the level of the filler supply conveyor 102 and which operates, whenever a new filler is needed upon said conveyor, to grip the lowermost filler in the stack and pull it positively down upon and into engagement with the impellers of the conveyor, while restraining the remaining fillers in the stack from following suit; and since stacks of fillers of the type described when assembled for shipping are tightly inter-engaged and often difficult to separate, the magazine of the invention may also be provided with mechanism 210 disposed adjacent its side walls 186a and 186b and operating through suitable apertures or windows 212a, 212b, 212c, 212d, 214a and 214b thereof at a substantially higher level than the hereinbefore mentioned filler dispensing mechanism, that separates the individual fillers of a stack and which permits only loose fillers to reach the previously mentioned filler dispensing mechanism. At the same time, said mechanism 210 is effective to prevent the full load of the stack of fillers from bearing down upon said filler dispensing mechanism 208.

When the filler separating mechanism 210 in the upper half of the magazine 104 passes a separated filler, said filler drops upon opposed pairs of tongues 218a, 218b

and 218c, 218d that project through the hereinbefore mentioned apertures 212a, 212b and 212c, 212d, respectively, into the interior of the magazine 104. Since the four tongues 218a, 218b, 218c and 218d are of symmetrically identical shape and construction, and since they all operate in a symmetrically identical manner, they will be collectively referred to in the following description by the numeral 218 alone, and will be individually identified by the suffix letters, *a*, *b*, *c*, and *d* only where necessary for a clearer understanding of their operation, and the same practice of identifying symmetrically identical elements will be followed with regard to components that form part of, or constitute auxiliary mechanisms, for said four tongues. Each of the tongues 218 is looped around, and turns upon, a stud 222 (FIG. 24) that projects laterally from a vertically disposed supporting arm 224. Downward rotation of each such tongue under the weight of a filler resting thereon is limited to a slightly downwardly slanting position by a stop web 228 that is rigidly secured to the looped tail end 229 of the tongue and which is arranged to strike with its upper edge against the outer face of the upper end of supporting arm 224.

Whenever the time approaches for a new filler to be delivered onto the filler supply conveyor 102, four claws 230a, 230b and 230c, 230d located intermediately of, and adjacent to, respective ones of the retaining tongues 218a, 218b and 218c, 218d, rise from below (FIGS. 16 and 21) and place the tips 234a and 234b of arcuately recessed retaining shelves 236 underneath the side edges 30 of the lowermost filler in the stack at a level that is lower than the level of the retaining tongues by a distance which is slightly larger than the thickness of the filler edges and somewhat smaller than the vertical distance between the side edges of two directly superposed fillers in the stack (FIGS. 17 and 21). The tail edge of each of the supporting shelves 236 forms a pair of axially spaced loops 238a and 238b that are engaged by and turn upon the laterally projecting opposite ends of a stud 240 held in a supporting arm 242. Downward rotation of each shelf 236 upon the projecting ends of stud 240 is opposed by a spring 246 which is housed in a suitable recess 248 provided in the outer face of arm 242 and which bears against a web 250 that is rigidly secured to the loops 238a and 238b (FIG. 25). Each of the shelves 236 is also provided with a flat gripping blade 252 that is formed by its tail edge intermediately of the loops 238a and 238b. Said blade extends in a direction inwardly of the magazine a distance above the upper surface of said shelf that is only very slightly larger than the thickness of the filler edges, and reaches to a point sufficiently short of the arcuately recessed edge to said shelf to permit the edge of a filler to rest safely upon said edge without interference from the gripping blade 252. As soon as the tips 234a, 234b of the four shelves 236 have moved underneath the side edges of the lowermost filler in the stack, and while their gripping blades 252 are still removed from said edges, the tongue supporting arms 224 tilt outwardly away from the side walls of the magazine and withdraw the four tongues 218 from underneath the lowermost filler so that said filler drops onto and comes to rest upon the tips 234a and 234b of the shelves 236 (FIGS. 17 and 21). At this moment the arms 242 of the claws 230 which up to this moment were in a reclining position (FIGS. 16 and 17) assume an almost vertical position (FIG. 18), pushing the shelves 236 deeper underneath the lowermost filler to such an extent that their gripping blades 252 engage over the side edges of said lowermost filler and enter the space between said lowermost filler and the side edges of the directly superposed filler as illustrated in FIGS. 18, 22 and 43. At almost the same time the tongue supporting arms 224 resume their initial positions and move the filler supporting tongues 218 into the space between the side edges of the two lowermost fillers as likewise illustrated in FIGS. 18, 22 and 43.

To insure that during this phase in the operation of

the filler dispensing mechanism the tongues 218 will be sufficiently spaced above the filler supporting surfaces of the shelves 236 to clear the side edges of the lowermost filler in the stack, each of the tongues 218 carries on its under side a rounded spacer head 254 (FIG. 24) that engages the filler supporting surface of its cooperating shelf 236; and to insure that the tongues 218 are never lifted to an excessive extent above the filler supporting surface of their cooperating shelves 236 which might cause them to strike against, or to slide over, the side edges of the directly superposed filler in the stack instead of sliding underneath said filler, spring means 256 bearing against the stop web 228 on the looped end 229 of each tongue below the stud 222 urge the tongues in clockwise direction as viewed in FIG. 24 to an extent limited by engagement of the upper edge of said stop web with the outer surface of the tongue supporting arm 224.

As the filler dispensing operation proceeds further, the claw supporting arms 242 move downwardly while retaining their vertical position and while the tongues 218 on arms 224 remain in their normal stack supporting position. In this manner the gripping blades 252 of the four claws 230 positively disengage the lowermost filler from the superposed stack of fillers as illustrated in FIGS. 19, 23 and 44 while the tongues 218 restrain the remaining filler stack from following suit. As soon as the claws 230 have lowered the lowermost filler to the level of conveyor 102, their arms 242 tilt outwardly away from the magazine side walls so that the shelves 236 are withdrawn from the side edges of said lowermost filler, and said filler drops onto said conveyor with the center cavities 130 of its leading and trailing pocket rows into engagement with two of the conical impeller members 126 of said conveyor. During further operation the reclined arms 242 of the claws 232 rise again and tilt inwardly to place the tips 234a and 234b of the filler supporting shelves 236 underneath the sides edges of the next lowest filler in the magazine directly below the filler supporting tongues 218 as illustrated in FIGS. 16, 21 and 41, and another cycle in the operation of the described filler dispensing mechanism 208 has commenced.

The described operations of the stack supporting tongues 218 and the filler disengaging claws 230 are powered by and occur in synchronism with the advance of the filler supply conveyor 102. Having reference to FIGS. 2, 7 and 8, the position of all four filler retaining tongues 218 is controlled by a cam 258 that is firmly mounted upon the conveyor drive shaft 112 in proximity of the left side panel 114a of the conveyor as viewed in FIG. 2. The cam 258 has a single recess 260 extending over slightly more than one-third of its contour which recess effects the above discussed relatively brief withdrawal of the tongues 218 from underneath the lowest filler in the magazine 104. The power train between cam 258 and the four filler retaining tongues 218a, 218b, 218c and 218d comprises a cam follower arm 262 that is firmly mounted upon a transverse shaft 264 which is suitably journaled in the side panels 114a and 114b of the conveyor frame. A cam follower roller 266 pivoted to the free end of arm 262 is held in engagement with the edge of cam 258 by means of a spring 268 that is tensioned between arm 262 and the hereinbefore mentioned cross channel 118 of the conveyor frame. Firmly secured to the outwardly projecting opposite ends of transverse shaft 264 are short, upwardly directed bar-shaped arms 270a and 270b (FIGS. 1, 8 and 26). The free end of each of said bars 270a and 270b is provided with a recess 272 that forms an arcuate camming surface 274 (FIGS. 8 and 26). The surfaces 274 of each of said arms 270a and 270b are engaged by rollers 276a and 276b, respectively, that are rotatably mounted upon the downwardly turned ends 278a and 278b of two horizontally disposed spindles 280a and 280b which are rotatably supported from and adjacent to the opposite side walls of the magazine, as best shown in FIGS. 1 and 8. Firmly

mounted upon and rising from the spindle 280a are the hereinbefore described tongue supporting arms 224a and 224c, and firmly supported on and rising from the spindle 280b are the tongue supporting arms 224b and 224d, which carry the stack retaining tongues 218 at such an altitude and in such a manner that they may move through respective ones of the hereinbefore mentioned apertures 204a, 204b, 204c and 204d in the magazine side walls near the upper ends of said apertures.

When the control cam 258 presents its sector 281 of larger radius to the cam follower roller 266, the bar-shaped arms 270a and 270b are in the rotary position illustrated in FIGS. 1, 8 and 26 wherein they present the thick portion 282 of their upper ends to their respective rollers 276a and 276b. As a result thereof the spindles 280a and 280b are in a rotary position wherein the arms 224a, 224c and 224b, 224d extend closely adjacent to the surfaces of the magazine side walls and the stack supporting tongues at their upper ends project fully into the magazine. Whenever during rotation of the conveyor drive shaft 112, the cam 258 presents its recess 260 to the cam follower roller 266, the spring 268 turns the shaft 264 in counterclockwise direction as viewed in FIGS. 8 and 26 which causes the camming arms 270a and 270b to present the thin portions 283 of their free ends to the rollers 276a and 276b, respectively. In this position of arms 270a and 270b a coil spring 284 tensioned between the downwardly turned ends 278 of the spindles 280a and 280b turns said spindles in counterclockwise and clockwise direction, respectively, which is effective to swing the arms 224a, 224c and 224b, 224d outwardly away from the magazine side walls withdrawing the tongues 218 from underneath the lowest filler in the magazine as illustrated in FIGS. 17 and 42. Then, when during further rotation of the conveyor drive shaft 112, the roller 266 on cam follower arm 262 climbs back onto sector 281 of control cam 258, the arms 270a and 270b move again their thick end portions 282 underneath the rollers 276a and 276b which is effective to swing the spindles 280a and 280b in counterclockwise and clockwise directions, respectively (FIG. 8). As a result thereof the arms 224a, 224c and 224b, 224d resume their upright positions and project the tongues 218 through the aperture 204a, 204c and 204b, 204d, respectively, into the interior of the magazine as illustrated in FIG. 5.

The hereinbefore described operation of the claws 230 which grip the lowermost filler of the stack within the magazine and force it downwardly into engagement with the impellers of the carton supply conveyor 104 involves actually two components of movement, namely a rectilinear vertical movement and a rotational movement about a horizontal axis outwardly away from and inwardly back to filler gripping position. The vertical movement of the claws is controlled by a pair of complementary cams 286 and 288 (FIGS. 2, 4 and 5) both mounted firmly upon the conveyor drive shaft 112 at opposite sides of sprocket 108. An upper sector of cam 288 (FIG. 4)—which is the cam that effects lowering of the claws—is engaged by a roller 290 (FIG. 4) pivoted to the free end of an arm 292. The arm 292 is firmly mounted upon a transverse shaft 294 that is suitably journaled in the side panels 114a and 114b of the conveyor frame. A lower sector of cam 286 (FIG. 5)—which is the cam that effects elevation of the claws 230—is engaged by a roller 296 that is pivoted to the free end of another arm 298. Arm 298 is likewise mounted upon the hereinbefore mentioned transverse shaft 294. The contour of cam 288 forms a single rise 300 of relatively short duration, and as the roller 290 on cam follower arm 292 is forced to ascend said rise during rotation of the drive shaft 112, the contour shaft 294 is turned in clockwise direction as viewed in FIGS. 4 and 8. During this phase in the operation of the conveyor shaft 112, the complementary cam 286 presents a re-

cess 302 of relatively short duration to the roller 296 on its cam follower arm 298 so that it does not interfere with the clockwise rotation of the counter shaft 294 (FIG. 5). However, after the roller 290 on arm 292 has negotiated the solitary rise 300 in the contour of cam 288, and while said roller encounters a steep descent 306 in the contour of said cam, the complementary cam 286 presents a gradual rise 304 to its cam follower roller 296. As a result the counter shaft 294 is gradually turned in counterclockwise direction as viewed in FIGS. 4, 5 and 8, and since cam 286 forms a lobe 308 of substantial angular width, said counter shaft 294 is held in a counterclockwise position for a substantial period of time. Engaged over the counter shaft 294 near the side panels 114a and 114b, respectively, of the conveyor frame are sleeves 310a and 310b and firmly secured to the undersides of said sleeves are arms 312a and 312b, respectively. The opposite ends of said arms are pivoted to interponents 314a and 314b, respectively, which in turn are pivoted to bosses 316a and 316b that are formed on blocks 318a and 318b which are located exteriorly of the opposite side panels 114a and 114b of the conveyor frame. The bosses 316a and 316b project inwardly into the space below the magazine through elongated vertical slots 319a and 319b formed in said side panels 114a and 114b. The two blocks 318a and 318b comprised in the filler dispensing mechanism are slideably mounted upon vertical guide rods 320a and 320b, respectively, whose lower ends are turned inwardly and are rigidly anchored in the adjacent side panels of the conveyor frame as shown in FIGS. 1, 3, 4, 5 and 8. Each of the blocks 318a and 318b carries in its upper end horizontally disposed spindles 322a, 322c and 322b, 322d, respectively, that extend parallel to the side panels of the conveyor frame and project from the opposite ends of said blocks, and rotatably mounted upon said spindles are bushings 324a, 324c and 324b, 324d, respectively, to which are rigidly secured the supporting arms 242a, 242c, and 242b, 242d of the hereinbefore described four filler-gripping claws 230a, 230c, 230b and 230d.

Whenever during rotation of the conveyor drive shaft 112, the counter shaft 294 is turned in a counterclockwise direction as viewed in FIGS. 4 and 5 by the action of control cam 286 as described hereinbefore, the resultant counterclockwise movement of the links 312a and 312b shifts the blocks 318a and 318b upwardly upon their guide rods 320a and 320b, respectively, and in this manner raises the filler-gripping claws 230 to almost the level of the stack retaining tongues 218 as described hereinbefore; and vice versa, whenever the complementary cam 288 forces the counter shaft 294 to swing in clockwise direction as viewed in FIG. 4, the resultant clockwise movement of the links 312a and 312b slides the blocks 318a and 318b downwardly causing the claws 230 to descend to the level of the filler supply conveyor 102 in a manner likewise explained hereinbefore.

It remains to explain how the filler-gripping claws 230 are caused to close in on the filler stack in the magazine at the upper end of their vertical travel to grip the lowest filler in the stack and how they are caused to withdraw from the magazine at the lower end of their vertical travel so that a filler held between said claws may drop freely onto, and be carried away by, the conveyor 102. To this end the claw supporting arms 242a, 242c and 242b, 242d on the opposite sides of the magazine are rigidly connected for movement in unison by cross bars 325a and 325b, respectively, and the opposed claw supporting arms 242a and 242b near the rear wall 192 of the magazine extend a substantial distance below the level of their spindles 322a and 322b, respectively, and carry at their lower ends studs 326a and 326b that extend in a direction parallel to the side panels 114a and 114b and which mount rollers 328a and 328b (FIG. 8). Torsion springs 330 disposed between the rotatable bushings 324a, 324c and 324b, 324d on spindles 322a, 322c, and 322b, 322d,

respectively, and the blocks 318a and 318b within which said spindles are secured constantly urge the rollers 328a and 328b into engagement with the outer surfaces of flags 332a and 332b, respectively, that are mounted for rotation about vertical axes in brackets 334a and 334b which are secured to the respective side panels 114a and 114b of the conveyor frame (FIGS. 1 and 8). Whenever the flags 332a and 332b are in a rotary position parallel to the side walls of the magazine and the side walls of the conveyor frame, the torsion springs 330 force the claw supporting arms 242 to assume the outwardly tilted position illustrated in FIGS. 16, 41 and 42 wherein the claws are withdrawn from the magazine, but whenever the flags 332a and 332b are swung into a rotary position wherein they slant angularly away from the adjacent side panels of the conveyor frame, the claw supporting arms 242 are swung into a position parallel to the side walls of the magazine wherein the claws close in on the lowermost filler in the magazine as shown in FIGS. 8, 18, 19, 20, 43, 44 and 45. As may be seen from both FIGS. 1 and 8, the flags 332a and 332b are of a vertical depth equal to the distance of the vertical travel of the claw supporting arms 242a and 242b. Hence, the flags 332a and 332b will appropriately control the rotary position of the claw supporting arms irrespective of whether the claws are in raised or lowered position.

To vary the rotary position of the two claw-control flags 332a and 332b comprised in the filler dispensing mechanism in the manner required for the hereinbefore described performance of the filler gripping claws, a fourth cam 336 is firmly mounted upon the conveyor drive shaft 112 (FIGS. 2 and 6). The edge of said cam is engaged by a roller 338 that is pivoted to an arm 340 which is firmly secured to, and rises from, a transverse counter shaft 342. The counter shaft 342 is suitably journaled in the repeatedly mentioned side panels 114a and 114b of the conveyor frame at points rearwardly of the conveyor drive shaft 112. Firmly secured to said counter shaft 342 and projecting radially therefrom are two downwardly directed rods 344a and 344b, one for each of the flags comprised in the claw control mechanism. Connected to said rods by universal joints 346a and 346b, respectively, are elongated links 348a and 348b (FIG. 8) that extend in a direction forwardly of the conveyor below the conveyor drive shaft to points approximately opposite the inner surfaces of the flags 332a and 332b. Another set of universal joints 350a and 350b, respectively, connects the inner ends of the links 348a and 348b to pitmans 352a and 352b that project outwardly through suitable apertures 354a or 354b (FIG. 3) in the adjacent side panels of the conveyor frame where they are rigidly secured to their respective flags 332a and 332b (FIG. 8).

The contour of cam 336 (FIG. 6) forms a recess 356 of relatively short duration from which it rises steeply to a two-stepped lobe 358. When the cam 336 presents its recess 356 to the cam follower roller 338, the flags 332a and 332b assume a position parallel to the side panels of the conveyor frame and as a result thereof, the filler-gripping claws 230 are fully withdrawn from the magazine as previously explained and as illustrated in FIGS. 16 and 41. During further rotation of the conveyor drive shaft 112, when cam 336 presents the first and lower sector 360 of its two-stepped lobe 358 to the cam follower roller 338, the flags 332a and 332b are swung outwardly away from the side panels of the conveyor frame to a limited extent, causing the claws 230 to shift the tips 234a and 234b of their supporting shelves 236 underneath the lowest filler in the magazine, but keeping their gripping blades 252 clear of the fillers in the magazine.

By the time the cam follower roller 338 has fully climbed the first and lower sector 360 of the two-stepped lobe 358 of cam 336, the cam 286 which controls the

upward movement of the claws 230 presents its sector 308 of largest radius to its cam follower roller 296, which means that the shelves 236 of the claws are positioned directly below the side edges of the lowest filler in the magazine. As may be seen from FIG. 6 and from FIGS. 41 to 45, the first and lower sector 369 of the two-stepped lobe 358 of cam 336 is angularly aligned on drive shaft 112 with the solitary recess 260 in the contour of the cam 258 that controls the position of the filler retaining tongues 218. This means that, as the shelves 236 of the claws 230 are moved underneath the lowermost filler in the magazine, the stack retaining tongues are withdrawn from the magazine, and as a result thereof the stack of fillers drops onto the tips 334a and 334b of said shelves 236. Then as the cam follower roller 266 of the lever train that determines the position of the stack retaining tongues 218 climbs out of the solitary recess 260 in its control cam 258 (FIG. 7) causing the tongues 218 to enter into the space between the side edges of the lowermost and the directly superposed filler in the filler stack, the flag control cam 336 presents the second and higher sector 362 of its two-stepped lobe 358 to the cam follower roller 338 causing the flags 332a and 332b to swing fully outwardly. This pushes the claws 230 deeper into the magazine so that their gripping blades 252 slide over the side edges of the lowermost filler underneath the side edges of the directly superposed filler in the filler stack. Directly thereafter the claw lowering cam 288 presents a steep rise 300 to its cam follower roller 290 causing the claws 230 to descend while their gripping blades 252 are engaged over the side edges of the lowermost filler and while the tongues 218 are in stack supporting position below the remaining filler stack in the magazine. Thus, the claws 230 grip and positively move the lowermost filler toward the conveyor 102 at the bottom of the magazine while the remaining stack of fillers is positively prevented from following suit.

When the cam follower roller 290 of the claw lowering cam 288 reaches the peak of the rise 300 in the contour of said cam, which means that the claws 230 have reached their lowermost portion, the cam follower roller 338 of the flag control cam 336 drops from the second and higher sector 362 of the two-stepped lobe 358 of said cam 336 into the solitary recess 356 which means that the flags 332a and 332b return to their inactive position wherein they extend parallel to the side panels 114a and 114b of the conveyor frame. As a result thereof, the torsion springs 330 withdraw the claws from the magazine so that the filler held between said claws is deposited upon the conveyor 102 which at that moment presents conical impeller members 126 to the center cavities of both the leading and trailing cavity rows on the underside of the filler.

Stack separating mechanism

As previously pointed out, when the fillers of the type here under consideration are stacked for shipping, they are frequently difficult to separate which is liable to place an undue burden on the described filler dispensing operation of the filler-gripping claws 230 and the stack retaining tongues 218. Also, the full stack of fillers represents a substantial weight, which when allowed to bear fully upon the stack retaining tongues, and the dispensing claws might harmfully interfere with the delicate operation of these components. Mechanism is, therefore, provided at higher levels in the magazine, that pre-separates the individual fillers of the stack delivered into said magazine and which prevents the whole load of the fillers in the magazine from ever bearing fully upon the filler retaining tongues 218 or the filler dispensing claws 230.

For this purpose a stack of fillers that is deposited into the magazine through the open upper end thereof, is not permitted to drop directly onto the retaining tongues 218 or the shelves 236 of the filler dispensing mechanism, but is first retained at a higher level by four

lugs 366a, 366b, 366c and 366d. Since these four lugs are of identical shape and operate in an identical manner, they will be collectively referred to in the following description by the reference numeral 366 alone, and will be individually identified by the suffix letters a, b, c, and d only when necessary for a clearer understanding of the structure and operation of the filler separating mechanism 210; and the same practice of identifying identical, or identically operating elements will be followed with regard to the other components and auxiliary devices of the filler separating mechanism 210.

The four lugs 366 project into the interior of the magazine through the hereinbefore mentioned four apertures 212a, 212b, 212c, and 212d in the side walls 186a and 186b of said magazine near the four corners thereof (FIGS. 1, 3 and 8). Externally of the magazine side walls the lugs 366 are secured to two horizontally disposed angle bars 370a and 370b, respectively, that extend parallel and adjacent to said side walls and which are secured to the lower ends of vertically disposed plates 372a and 372b, respectively, whose upper edges are hingedly supported from the side walls of the magazine as shown at 374a and 374b, respectively, and which are outwardly arched in their lower halves as shown at 376a and 376b for reasons that will presently appear. Leaf springs 378a, 378c and 378b, 378d secured to the side walls 186a and 186b of the magazine at the outer surfaces thereof urge the bars 370a and 370b yieldably against said side walls so that the lugs 366a, 366c and 366b, 366d supported from said bars project fully into the interior of the magazine (FIG. 13). Downwardly directed spring fingers 380a, 380b, 380c and 380d are secured to the outer surfaces of the magazine side walls near the four corners thereof and project into the interior of the magazine through the hereinbefore mentioned apertures 212a, 212b, 212c and 212d, respectively, with their inwardly turned tips 382 located above the level of the lugs 366 at a distance that is larger than the thickness of the side edge of a single filler. Hence, the side edges of the lowermost filler of a new stack deposited into the magazine through the open upper end thereof, when they come to rest upon the lugs 366, have passed said finger tips 380 and are positively restrained from ever returning to a higher level by said finger tips, as shown in FIG. 13.

Means are provided that operate to withdraw the lugs 366 from underneath the lowermost filler of a stack of fillers while gripping said stack laterally and lifting it by a distance sufficient to detach it completely from the lowermost filler, so that the latter having lost contact with the superposed fillers in the stack, and devoid of the support formerly afforded by the lugs 366 drops individually onto the retaining tongues 218 of the filler dispensing mechanism underneath or upon whatever pre-separated loosely superposed fillers may previously have accumulated upon said retaining tongues.

For this purpose horizontal spindles 384a and 384b are rotatably supported from the magazine side walls 188a and 188b, respectively, a limited distance above the angle bars 370a and 370b and extend within the outwardly arched portions 376a and 376b of the plates 372a and 372b that support said angle bars; and clamped to said spindles 384a and 384b at points adjacent and above the four retaining lugs 366a, 366b, 366c and 366d by suitable metal clamps 386 are rectangular blocks 388a, 388b, 388c, and 388d, respectively, of an elastic material, such as rubber. Said rubber blocks are of such size in the direction radially of the spindles 384a and 384b that their rotary orbits extend into the interior of the magazine 104 through the hereinbefore mentioned apertures 212a, 212b, 212c and 212d, respectively, in the side walls 188a and 188b thereof.

During operation of the filler packing machine the spindles 384a and 384b are driven in counterclockwise and clockwise directions, respectively, as viewed in FIG.

8, so that the rubber blocks 388 enter the interior of the magazine from below and come into contact with the side edges of the tightly packed stack of fillers that rests upon the lugs 366 within the magazine. As the blocks 388 pass upwardly through the interior of the magazine, they lift the stack of fillers a limited distance above the spring fingers 380 as illustrated in FIG. 14 except for the lowermost fillers which are restrained by the tips of said fingers, and are, therefore, separated from the stack. At the same time the spindles 384a and 384b actuate means that withdraw the lugs 366 from the magazine so that the lowermost filler, after it has been separated from the remaining stack in the described manner, may drop individually onto the retaining tongues 218 of the filler dispensing mechanism underneath, as likewise shown in FIG. 14. For this purpose each of the spindles 284a and 284b carries a disc 392 (FIGS. 8 and 13 to 15) that passes through an L-shaped aperture 394 in the adjacent lug-supporting plate 372a or 372b, respectively, and also through the hereinbefore mentioned aperture 214a or 214b in the adjacent magazine side walls, and which possesses an axially projecting eccentric stud 396 that is too long to clear the upper leg 395 of said L-shaped aperture 394. Hence, when said stud 396 comes against the inner face of the adjacent lug-supporting plate 372a or 372b, respectively, near the upper end of the L-shaped aperture 394 thereof, it forces said plate to swing outwardly away from the adjacent side wall of the magazine which is effective to withdraw the lugs 366 from the interior of the magazine.

To extend the period of time during which the rubber blocks 388 keep the stack within the upper end of the magazine in raised position, the two rubber blocks 388a, 388c, or 388b, 388d that are mounted upon a common spindle may be clamped upon their spindles in rotary positions that are displaced from each other by a suitable angle, such as 45°, while the diametrically opposite rubber blocks, i.e. blocks 388a, 388d and 388b, 388c, respectively, are arranged to operate in synchronism as shown in FIG. 8. In such a case the rotary position of the studs 396 that effect withdrawal of the lugs 366 on the discs 392 should be such that they engage their respective plates 372a and 372b, and begin to push them backwards as soon as the leading rubber blocks 388a and 388d on spindles 384a and 384b, respectively, have fully entered the magazines through the apertures 212a and 212d (FIG. 14).

To operate the spindles 384a and 384b, their rear ends are provided with mitre gears 398a and 398b, respectively, that mesh with mitre gears 400a and 400b which are firmly secured to the opposite ends of a transverse shaft 402 that is rotatably supported from the rear wall 192 of the magazine (FIG. 8). Said transverse shaft 402 carries also a sprocket 404 that is operatively connected by an endless sprocket chain 406 with another sprocket 408 which is firmly mounted on and turns with the conveyor drive shaft 112 (FIG. 2). The operation of the described stack separating mechanism 210 should preferably be timed with the operation of the hereinbefore described filler dispensing mechanism 208 in such a manner that the filler retaining lugs 366 of the former lift the stack of fillers at the very moment when the tongues 218 of the latter move into stack supporting position so that the filler dispensing mechanism will not have to bear the weight of the total stack in the magazine during the filler dispensing operations.

By the time the trailing rubber blocks 388b and 388c leave the interior of the magazine through the upper ends of the windows 212b and 212c, respectively, releasing the raised stack of superposed fillers, the camming studs 396 on discs 392 move exteriorly of, and parallel with, the outwardly arched portions 376a and 376b of the hinge plates 372a and 372b, respectively. Thence, the leaf springs 378a, 378b, 378c and 378d may return said plates and the lug supporting angle bars 370a and

370b to their initial positions adjacent the magazine side-walls and the lugs 366a, 366b, 366c and 366d are again projected into the interior of the magazine and prevent the filler stack that has just been released by the rubber blocks 388b and 388c, from dropping onto the retaining tongues 218 of the filler dispensing mechanism 208 (FIG. 15).

Egg supply conveyor

The conveyor 100 that carries the eggs to be packed, over the hereinbefore described filler supply conveyor 102 for deposition into the pockets of a filler on said last mentioned conveyor 102, comprises a pair of parallel, transversely spaced endless chains 410a and 410b (FIGS. 1, 27 and 28), the opposite ends of which are trained over suitable drive and idler sprockets (only the idler sprockets 411a and 411b being visible in FIG. 1). Held between the chains 410a and 410b is an endless sequence of egg supporting buckets 412. Said buckets have the form of downwardly converging open ended shells that are adapted to receive and support eggs at their diverging upper ends, and which may be operated to drop said eggs through their lower ends at predetermined points along the upper run of the egg supply conveyor. For this purpose each of said buckets is formed by two segments in the form of semi-cylindrical shells 414 and 416 that face each other with their concave surfaces (FIG. 28). Adjacent their side edges, and near their upper ends, said shells are provided with outwardly directed tubular bosses 418a, 418b and 420a, 420b, respectively, within which are rotatably received transversely aligned elongated pivot pins 422a and 422b of the two parallel sprocket chains 410a and 410b, respectively. Intermediately each two consecutive buckets the parallel chains of the egg supply conveyor may be connected by cross rods 424, as shown. The bosses 418b and 420b on the right side of the bucket segments, as viewed in the direction of movement of the egg supply conveyor, carry firmly secured thereto enmeshed gear segments 426 and 428, respectively, and the leading gear segment 426 of each bucket forms an upwardly directed actuating nose 430 whose leading surface is rearwardly slanted as shown at 432. A suitable spring 434 tensioned between points of said segments 426 and 428 below the bosses 418b and 420b, respectively, urges the semi-cylindrical shells of each bucket into a closed position as illustrated in FIG. 28, wherein they properly support an egg delivered thereto at the diverging upper end thereof.

Suitably supported from the front wall 198 of the filler magazine 104 is a shelf 436 which carries a battery of six solenoids 440, one above each of the pockets in the vertically aligned pocket row of a filler on the filler supply conveyor underneath. While these solenoids have above been collectively indicated by the reference numeral 440, they may hereinafter be individually identified by the reference numerals 441 to 446, respectively, wherever necessary in the following description of the egg packing machine for a clearer understanding of my invention.

Each of the solenoids 440 is arranged, upon energization, to project momentarily an actuating ledge 448 into the path of the noses 430 on the segments 426 of predetermined egg supporting buckets 412 as they pass over the filler supply conveyor 102. As the rearwardly slanted leading edge 432 of a nose 430 on the segment 426 of a bucket 412 comes against such a ledge 448 in projected position, said segment 426 is forced to swing in clockwise direction, as viewed in FIGS. 27 and 28, against the urgency of spring 434. Clockwise movement of the leading segment 426 moves the trailing segment 428, which is enmeshed therewith, in counterclockwise direction and as a result thereof the lower ends of the two semi-cylindrical shells 414 and 416 are forced to swing apart, as illustrated at 450 in FIG. 27, and are therefore no longer capable of supporting an egg, so that any egg that may be seated in the bucket at the moment will drop through its opened lower end into the pocket of a filler underneath.

Since the egg supply conveyor 100 is continually in motion during operation of the machine, and moves relatively fast, an egg released from a bucket 412 does not drop from the bucket in a straight line but forms a parabolic trajectory. The position of the actuating ledges 443 relative to the corresponding pockets of a filler on the filler supply conveyor 102 should therefore be such that they engage the leading gear segments 426 of the buckets before the buckets reach a position in exact vertical alignment with the pockets presented to them by the fillers on the filler supply conveyor underneath. Hence, the parabolic trajectory of an egg dropped from an advancing bucket 412 will lead it directly into its proper pocket.

The control mechanism

To drop the eggs in proper order from the egg supply conveyor 100 into the pockets of a filler on the filler supply conveyor 102, a mechanism that operates in synchronism with the advance of the egg supply conveyor, and which senses the presence of eggs in the buckets of said conveyor, causes energization of the bucket opening solenoids 440 in the proper sequence commencing with the solenoid 446 on the downstream side of the egg packing unit; and after six eggs have been dropped from the egg supply conveyor 100 into the six adjacent pockets of a pocket row in the filler on conveyor 102, said control mechanism which has hereinbefore been identified by the reference numeral 105 (FIG. 1) causes brief energization of the previously described ratchet-release solenoid 170 to effect engagement of clutch 150 and permits the conveyor 102 to advance by a distance that will bring the directly succeeding pocket row of the filler, or the leading pocket row of a directly succeeding filler, as the case may be, into egg receiving position below the egg supply conveyor 100, whereupon said control mechanism 105 operates again to energize the bucket opening solenoids 440 in their proper sequence to fill another pocket row with eggs.

As an egg on the egg supply conveyor 100 approaches the filler supply conveyor 102 and moves through a point of predetermined distance before the downstream side of a filler on said conveyor—which distance is equal to the length of six consecutive buckets 412 in the exemplary embodiment of the invention that I am about to describe—it encounters a resilient sensing finger 454 (FIG. 27) that projects from above into the path of the upwardly protruding ends of the eggs in the buckets of the egg supply conveyor. Said sensing finger forms part of the actuating arm 456 of a normally open switch 458 (FIGS. 27 and 40) which is suitably supported from the frame 460 of the egg supply conveyor 100, and which is briefly closed whenever an egg in a bucket 412 engages the sensing finger 454 and pushes it out of its path. Whenever the switch 458 is closed, it sets into motion mechanism that will release the egg which caused its closure from its supporting bucket 412 at the very moment when said bucket travels over an empty pocket in the filler held underneath the egg supply conveyor 100 by the filler supply conveyor 102. If the filler pocket row in alignment with the egg supply conveyor is entirely empty, said mechanism is arranged to effect discharge of the egg from the egg supply conveyor into the pocket at the downstream end of said pocket row, and succeeding eggs on said egg supply conveyor 100 are successively dropped into the remaining five pockets in an upstream direction.

The control mechanism 105 is basically a memory device that operates in synchronism with the egg supply conveyor 100, and which comprises a vertical shaft 462 that may be rotatably supported from the hereinbefore mentioned shelf 436 by means of two vertically superposed brackets 464 and 466 (FIG. 1). Supported from the vertical shaft for rotation therewith is a pair of vertically spaced mounting discs 468 of which only the upper one is visible in FIGS. 29 and 30. Said discs are provided with eight angularly equi-spaced, vertically aligned mounting slots 470 and received within, and secured to, verti-

cally aligned ones of said slots are eight short, vertically disposed channels 472 of U-shaped cross section whose open sides face in outward direction. Pivottally supported within each of said channels for rotation about a horizontal axis is a memory pin 474 which may be of steel, but is preferably made of nylon, and which projects with one of its ends beyond the periphery of the rotor 476 formed by the discs 468 and the channels 472. The rotation of each memory pin 474 about its horizontal pivot is positively limited by studs 480 and 482 that are mounted within the side flanges of the channels 472 above and below the pins as shown in FIG. 29, and which determine the ineffective and effective positions, respectively, of said pins.

Disposed below the circular row of pins 474 is a base plate 484 of horseshoe shape that embraces the rotor 476, and which may be supported at its ends by two vertical rods 486a and 486b which are in turn supported from the hereinbefore mentioned vertically spaced brackets 464 and 466 (FIG. 1).

Arranged along the inner edge of the horseshoe plate 484 for driving engagement by the memory pins 474 is a semi-circular row of six Geneva gears 491, 492, 493, 494, 495 and 496 which may be made from a plastic material (FIGS. 29 and 30). Each of said Geneva gears has six equi-spaced notches 497, corresponding to the six egg discharge effecting solenoids 440, which notches are adapted to be operatively engaged by the protruding end of the memory pins 474 when said pins are in effective, i.e. depressed position. Each Geneva gear possesses a tubular stem 498 (FIG. 31) that turns upon a vertical stud 499 which rises from a common U-shaped mounting plate 500 that is adjustably supported upon the horseshoe plate 484. Arranged along the outer periphery of the semi-circle formed by the six Geneva gears are six switches 501, 502, 503, 504, 505 and 506, that lie in the individual power circuits (FIG. 40) of the six consecutive bucket release solenoids 441 to 446 which are disposed adjacent the egg supply conveyor 100 above the filler supply conveyor 102. The switches 501 to 506 are bolted to the U-shaped mounting plate 500, and their position is controlled by cams 508 formed on the stems 508 of the Geneva gears (FIGURE 31) depending upon the rotary position of said gears. The edges of said cams 508 have each a solitary depression 510, as shown in FIGURES 30, and 32 to 39, and as long as a roller 512 provided on the actuating arm 514 of each of said switches rides upon the circular contour 516 of its respective cam, the switch is held in open position, but when it drops into said depression 510 the switch will close.

During operation of the machine the rotor formed by the discs 468 and the channels 472 turns in counter-clockwise direction as viewed in FIG. 30 in synchronism with the egg supply conveyor 100 such that at a given time interval the same number of memory pins 474 will pass a stationary point as do buckets 412 on the egg supply conveyor. For this purpose the lower end of the vertical shaft 462 may be provided with a bevel gear 518 of suitable size which meshes with another bevel gear 520 that is secured to the idler shaft 522 at the leading end of the egg supply conveyor (FIG. 1). During rotation of rotor 476 the memory pins 474 which project from the channels 472 sweep ineffectively above the Geneva gears 491 to 496, as long as they are in their upwardly tilted ineffective positions. Mounted upon the horseshoe plate 484, however, ahead of the first Geneva gear 491 is a solenoid 524 (FIGURE 30) that is energized by closure of the hereinbefore described egg sensing switch 458 (FIGURE 40). The armature 526 of the solenoid 524 is shaped in the manner of a T, with its cross bar 528 positioned slightly above the level of the circular row of memory pins 474 as long as the solenoid 524 is in de-energized condition. Upon energization of the solenoid 524, however, which is indicative of the approach of an egg on the egg supply conveyor 100, the

cross bar 528 of armature 526 bears down upon a passing pin and shifts it into its downwardly tilted effective position wherein it will successively engage and advance every one of the adjacent six Geneva gears over a limited increment.

The six Geneva gears upon the U-shaped plate 500 are adjusted to such rotary positions relative to each other that the depressions in the cams 508 of consecutive gears, counting backwards from the last gear 496, trail behind each other by rotary increments equal to the rotary increments by which the gears are advanced when effectively engaged by a memory pin. Initially, i.e., before an egg has been dropped into any of the pockets in the pocket row of a filler that is held below the egg supply conveyor, the Geneva gears are in the position illustrated in FIG. 32 wherein the sixth Geneva 496, i.e., the gear that is last engaged by a memory pin in depressed condition, is in such a rotary position that the depression 510 of its cam 508 lies directly in front of the roller 512 of its associated switch 506, which is the switch that closes the power circuit of the last one 446 of the set of bucket opening solenoids 440 (FIG. 40) i.e., the solenoid on the downstream side of the filler supply conveyor (FIG. 27). Thus, whenever the solenoid 524 depresses a memory pin 474, indicating that an egg approaches the packing station on the egg supply conveyor, consecutive engagement of said depressed pin with the consecutive Geneva gears 491 to 496 will advance all of said gears by a limited increment which remains without effect upon the switches 501 to 505 associated with the first five Geneva gears 491 to 495, respectively, but causes the roller 512 of the sixth switch 506 to drop briefly into depression 510 in the cam 508 of the sixth Geneva gear 496, as illustrated in FIG. 33. This closes the switch 506 temporarily, and as a result thereof the last solenoid 446 in the battery of bucket-opening solenoids 440 is energized and projects its armature into the path of the noses 430 of the conveyor buckets 412 at the very moment when the bucket carrying the egg which started the described sequence of operations, approaches said solenoid 446, because the pins 474 of the control device 105 advance in synchronism with the advance of the buckets on the egg supply conveyor, as previously pointed out. Hence, the egg will drop into the last pocket of the filler pocket row presented to the egg supply conveyor at the packing station.

As previously pointed out, however, passage of the above described memory pin 474 in depressed condition past the Geneva gears did not only advance the last Geneva gear 496, it also advanced each of the five preceding Geneva gears 491 to 495 by the same increment so that it is now the fifth Geneva gear 495 that holds the depression 510 of its cam 508 directly in front of the roller 512 of its associated switch 505. Hence, when the pin-activating solenoid 524 is again energized by the approach of an egg on the egg supply conveyor, and another memory pin 474 is depressed, said pin while advancing all the Geneva gears by equal rotary increments will cause the fifth Geneva gear 495 to effect closure of its respective switch 505 (FIG. 34) with resultant energization of the fifth solenoid 445 in the battery of bucket-opening solenoids 440.

As best illustrated in FIG. 30, the fifth Geneva gear 495 is spaced from the sixth Geneva gear 496 by an angular interval that is smaller than the angular interval between each two consecutive memory pins 474 on rotor 476 by a ratio equal to the ratio of the linear interval between the center points of consecutive egg receiving filler pockets to the linear interval between the center points of consecutive buckets on the egg supply conveyor. Measured in angular distance, the fifth Geneva gear 495 is, therefore, closer to the sixth and last Geneva gear 496 than the angular interval between two directly consecutive memory pins 474 on rotor 476, and the second memory pin 474 in depressed condition must, there-

fore, travel a longer distance counted from the point, of its rotary orbit, that corresponds to the egg sensing point at which the described sequence of operations is started, to the fifth Geneva gear 495 than corresponds to the linear dimension of five consecutive buckets on the egg supply conveyor. As a result, thereof, the bucket that carries the egg which caused depression of the second memory pin 474, will travel a distance slightly larger than the width of five buckets from the egg sensing point until its representative pin 474 on rotor 476 effects energization of the fifth bucket-opening solenoid 445 through actuation of the fifth Geneva gear 495. The bucket will, therefore, reach said solenoid 445 at the very moment when it projects its armature into the path of its nose 430 and hence the second egg supplied by conveyor 100 will drop into the fifth filler pocket which is the second pocket counted from the downstream side of the packing station. As the pin activating solenoid 524 depresses additional memory pins 474 indicative of the fact that additional eggs have come within the length of six buckets from the downstream side of the packing station the Geneva gears 491 to 496 are consequently advanced by additional increments causing in succession closure of the fourth, third, second, and first switches 504, 503, 502 and 501, respectively, as illustrated in FIGS. 35, 36, 37 and 38 with resultant energization of the fourth, third, second and first bucket opening solenoids 444, 443, 442 and 441, respectively, which open succeeding buckets 412, as they carry eggs over the fourth, third, second and first filler pocket counted from the upstream side of the packing station. In this manner all the pockets in the pocket row of a filler presented to the egg supply conveyor by the filler supply conveyor are successively filled with eggs.

After all six switches 501 to 506 of the control mechanism 105 have been consecutively closed, and all six pockets of a filler pocket row presented to the egg supply conveyor have been filled with eggs, the filler which forms said pocket row must be shifted so that a consecutive row of pockets will lie below the egg supply conveyor, before another egg is released from said conveyor under control of mechanism 105. Means is therefore provided in accordance with the invention that causes advance of the filler underneath the egg supply conveyor so as to place a new row of pockets underneath said conveyor whenever an egg has been dropped into the last pocket of the preceding pocket row. Release of the egg that dropped into said last pocket was effected by operative engagement of a depressed memory pin 474 with the first Geneva gear 491 in the sequence of six Geneva gears, which engagement caused temporary closure of the switch 501 that energizes the first solenoid 441 of the battery of bucket opening solenoids 440 (FIGURES 27, 38 and 40). After having actuated said first Geneva gear 491, the depressed pin 474 engages, and advances, consecutively all the remaining Geneva gears 492 to 496, as previously explained. The incremental advancement of the second Geneva gear 492 by said memory pin 474 is arranged to move the depression 510 in the cam 508 of said second Geneva gear 492 past the arched actuating end 530 of another normally open switch 532 (FIGS. 29, 30, 39 and 40) to cause brief closure thereof. The switch 532 is located between the first and second egg-releasing switches 501 and 502, respectively, as shown in FIGS. 29 and 30, and lies in the power circuit of the hereinbefore described ratchet release solenoid 170 (FIGS. 2, 11, and 40) below the drive shaft 112 of the filler supply conveyor. As a result the solenoid 170 is energized and withdraws the latching pawl 162 from the ratchet 158 permitting said ratchet to follow the rotative force of the driven side of clutch 150 which causes engagement of said clutch. The filler supply conveyor 102, therefore, commences to advance moving the filled pocket row of a filler beyond the egg supply conveyor, while advancing a directly succeeding pocket row into egg-

receiving position below said egg supply conveyor. However, the switch 532 remains closed only for a fraction of the brief moment during which the memory pin 474 advances the second Geneva gear 492, and will have returned to open position by the time the memory pin that caused its closure disengages itself from the second Geneva gear 492. In consequence thereof the ratchet release solenoid 170 is energized for only the brief period necessary to withdraw the nose 166 of pawl 162 from whatever tooth of the ratchet it engaged, and will immediately thereafter return into contact with the back of said tooth under the urgency of restore spring 172. The pawl 162, therefore, engages the directly succeeding tooth of the ratchet and causes disengagement of the clutch 150 so that rotation of the conveyor drive shaft 112 is limited to an angular interval that is determined by the back of the previously engaged tooth; and since the backs of the ratchet teeth are dimensioned to correspond with the conveyor advances necessary to place the successive pocket rows of a filler on the conveyor 162 into egg-receiving position relative to the egg supply conveyor 100, as previously explained, the described arrangement causes the filler supply conveyor 102 to advance at all times the proper distance to place a new pocket row underneath the egg supply conveyor whenever necessary. At the same time, since the filler dispensing mechanism 208 is powered by, and synchronized with the rotation of the conveyor drive shaft 112, as previously explained, the described operation of said conveyor drive shaft causes the filler dispensing mechanism of the magazine to deliver a new filler onto the conveyor 100, and into engagement with impellers 126 of the conveyor chain 106 whenever a previously deposited filler has moved fully out from underneath the magazine 104.

Reverting to the control device 105, after the memory pin 474 that caused release of the last or sixth egg into the last pocket of a filler pocket row, has passed the second Geneva gear 492 where it initiated the above described operations for placing another row of pockets underneath the egg supply conveyor, it passes all the remaining Geneva gears 493-496 advancing them by rotational increments corresponding to the angular distance between two consecutive ones of their notches 497, and in passing the sixth Geneva gear 496 it placed the same into its initial position as illustrated in FIG. 32 wherein the switch actuating depression 510 in its cam 508 lies again directly ahead of the actuating roller 512 of the power control switch 506 for the sixth egg-release solenoid 446. Hence, engagement of said sixth Geneva gear 496 by a subsequent memory pin 474 in depressed condition will cause said sixth egg releasing solenoid 446 to drop a first egg into the next pocket row presented to the egg supply conveyor. Thus, when another egg approaches the packing station and causes energization of the pin-depressing solenoid 524 the memory pin 474 depressed by energization of said solenoid will have to travel all the way to the sixth Geneva gear 496 (FIG. 30) before it causes energization of an egg-release solenoid. The next egg released from the distributing conveyor is dropped into the sixth pocket on the downstream side of the new pocket row that has meanwhile been moved below the egg supply conveyor. Due to the fact that a pocket row receives its last egg from the egg supply conveyor at the upstream side of the packing station, and the next egg to be released from the egg supply conveyor—which is the first egg to be dropped into the succeeding pocket row—is dropped into the pocket on the downstream side of the packing station, ample time is provided for the operations that move a new filler into egg-receiving position below the egg supply conveyor.

After a memory pin 474 in depressed condition has consecutively passed and actuated all six Geneva gears 491-496, it must be restored to ineffective position so that it may again be shifted to represent an approaching

bucket 412 that carries an egg. For this purpose, an upwardly slanting camming plate 534 is provided at the rear end of the rotor 476 adjacent the circular row of memory pins 474; and, after a depressed memory pin 474 has passed the sixth Geneva gear 476, it slides over the lower end of the camming plate 534, and as the pin continues its rotary course, it is cammed upwardly into its ineffective position.

Operation

To operate the described packing machine, the egg supply conveyor 100 is set into motion and also the motor (not shown) which applies power to the filler supply conveyor 102, without however actually moving said conveyor due to the fact that the latching pawl 162 engages a tooth of the ratchet 152 and in this manner maintains the clutch 150 in disengaged condition. A stack of fillers is placed into the magazine and comes to rest upon the inwardly projected lugs 366a, 366b, 366c, 366d of the stack separating mechanism. In readying the machine for practical operation it is then necessary to manually withdraw the pawl 162 from the ratchet 152 and permit operation of the conveyor drive shaft 112 until the lowermost filler in the stack has been worked through the stack separating and filler dispensing mechanisms, has been deposited onto the conveyor guide bars 136a, 136b, 138a and 138b into engagement with two impellers 126 and has been advanced along said guide bars until its leading row of pockets has been disposed below with the upper run of the egg supply conveyor. First, the four rubber blocks 388a, 388b, 388c, and 388d of the stack separating mechanism 210 engage the stack of fillers at its flanks and lift it within the magazine, while the spring fingers 380a, 380b, 380c, 380d positively prevent the lowermost fillers from upward movement, and in this manner separate them from the stack. As this is accomplished, the lugs 366a, 366b, 366c, and 366d are withdrawn from the magazine and the lowermost fillers drop upon the tongues 218a, 218b, 218c, 218d of the filler dispensing mechanism which tongues protrude into the magazine at this moment. Then as the rubber blocks 388a, 388b, 388c, and 388d drop the remaining stack of fillers, the lugs 366a, 366b, 366c, and 366d return to their inwardly projected position and prevent said unseparated stack from dropping onto, and burdening down, the filler dispensing mechanism.

In the meantime the shelves 236 of the filler dispensing claws 230 have moved their tips 234a and 234b underneath the side edges of the lowermost filler at points adjacent to and slightly below the retaining tongues 218, whereupon said tongues are briefly withdrawn so that the filler comes to rest upon the tips of said shelves 236. Now the claws 230 move closer in upon the lowermost filler and slip their gripping blades 252 over the side edges of said filler, while the retaining tongues 218 return at the same time to their original inwardly projected positions, and move over the side edges of the lowermost filler to prevent any additional fillers that may have been passed by the stack separator mechanism, from dropping upon the filler dispensing claws 230 as the latter descend to the level of the conveyor guide bars 136a, 136b, 138a, 138b, with the lowermost filler securely held between their gripping blades 252 and their shelves 236. As soon as the claws 230 have thus positively lowered the filler to the level of the conveyor bars, they are retracted from the magazine and in this manner drop the filler with the center pockets of its leading and trailing pocket rows into engagement with two impellers 126 of the conveyor chain 106. Thereupon, the claws 230 rise in retracted position to close in again upon the magazine when they reach a level slightly below the level of the retaining tongues 218 which latter remained in inwardly projected position during the described sequence of operations to prevent premature descent of any subsequent fillers that may have been passed by the separator mechanism 210 and may

have accumulated in the space between the lugs 366 of the latter and the tongues 218 of the filler dispensing mechanism 208.

As the conveyor drive shaft 112 continues to turn, it delivers the filler with its leading pocket row into a position below, and in vertical alignment with, the upper run of the egg supply conveyor 100, while the filler dispensing mechanism 208 deposits another filler onto the conveyor 102 as soon as the first filler has moved out from underneath the magazine.

With the leading pocket row of the first filler located in egg receiving position relative to the egg supply conveyor, the latching pawl 162 is now allowed to re-engage the ratchet 158 so that the filler supply conveyor 102 comes to a halt. At this stage in the operation of the egg packing machine the latching pawl 162 engages the first tooth 176 of the four short-backed teeth of ratchet 158 (FIG. 11).

Eggs may now be delivered into the buckets 412 of the egg supply conveyor 100. This may be done manually or it may be accomplished by suitable egg supply chutes and/or egg transfer mechanism such as are described in my co-pending patent applications, Serial Nos. 358,621 and 400,466, filed on June 1, 1953, and December 28, 1953, respectively. The latter is now Patent No. 2,895,274, July 21, 1959. From now on the egg packing machine of my invention operates completely automatically to pack eggs into fillers, and will continue to do so as long as eggs are delivered into the buckets 412 of the egg supply conveyor and filler stacks are deposited into the magazine 104. As an egg approaches the packing station, it strikes against the yieldable sensing finger 454 (FIG. 27) and causes closure of switch 458 (FIG. 40) which energizes the solenoid 524 (FIGS. 29 and 30) causing its armature 526 to strike downwardly at the very moment when a memory pin 474 passes underneath. In this manner said memory pin 474 is depressed from ineffective to effective Geneva gear advancing position. The shaft 462 of the control device 105 which turns as long as the egg supply conveyor 100 is in motion, turns the activated memory pin 474 in synchronism with the advance of the egg here under consideration toward and over the packing station. As the particular pin 474 passes the six Geneva gears 491 to 496, it advances each of them by a small increment, and when advancing the last of said gears, it effects closure of switch 506 (FIG. 33) causing energization of the last solenoid 446 (FIG. 40) in the battery of six solenoids that flank the egg supply conveyor 100 above the filler supply conveyor 102 (FIG. 27). Energization of said solenoid 446 projects its actuating ledge 448 into the path of the nose 430 on the bucket 412 that carries the egg here under consideration causing the bucket to open up and drop the egg into the last pocket, i.e., the pocket on the downstream side of the first or leading pocket row of the filler presented to the egg supply conveyor 100 by the filler supply conveyor 102.

Then, as soon as another egg approaches the packing station on the egg supply conveyor, and irrespective of whether this egg is seated in the directly succeeding bucket or whether several buckets are empty and it is a later bucket that carries the next egg, the cycle of operations repeats itself. Switch 458 is closed, solenoid 524 is energized, a pin 474 of rotor 476 corresponding to the bucket that carries the egg is depressed and the depressed pin advances all six Geneva gears 491 to 496 by a small increment. This time it is the fifth Geneva gear 495 whose rotation is effective to close its associated switch 505 (FIG. 34) causing energization of the fifth bucket opening solenoid 445, and as a result thereof the second egg to be packed is dropped into the fifth pocket of the leading pocket row of the filler underneath the egg supply conveyor 100. In an analogical manner successive eggs cause successive energization of fourth, third, second and first bucket opening solenoids 444, 443, 442, and 441 by closure of the switches asso-

ciated with the fourth, third, second and first Geneva gears respectively, as illustrated in FIGURES 35, 36, 37, and 38, respectively, and accordingly, the fourth, third, second and first pockets of the filler on the conveyor 102 are filled with eggs.

The activated memory pin 474 that caused release of an egg from the egg supply conveyor 100 above the pocket on the upstream side of the filler, by turning the Geneva gear 491 over a limited increment, as illustrated in FIG. 38 causes also closure of switch 532 when it turns the next Geneva gear 492, as illustrated in FIG. 39. Closure of switch 532 causes energization of the ratchet release solenoid 170 (FIGS. 2, 11, and 40) below the drive shaft 112 of the filler supply conveyor. The latching pawl 162 is therefore withdrawn from tooth 176 of the ratchet 158, the clutch 150 is engaged, and the drive shaft 112 advances the conveyor 102 by a distance determined by the angular width of the back of said tooth 176 which places the second pocket row of the filler into egg receiving position below the egg supply conveyor. Thereafter, it is the second pocket row of the filler that is filled with eggs in the manner described hereinbefore, and after an egg has been deposited into the pocket of said row on the upstream side of the filler, the ratchet release solenoid 170 is again energized permitting the conveyor 102 to advance the filler by a distance determined by the angular width of the back of the second ratchet tooth 178, which places the third pocket row of the filler into egg receiving position underneath the egg supply conveyor.

Finally, after an egg has been deposited in the described manner into the pocket on the upstream side of the fifth and last pocket row of the filler, the ratchet release solenoid 170 is again energized and withdraws the pawl 162 from the fifth tooth 184 of ratchet 158. The back of said fifth ratchet tooth 184 is of materially larger angular width than the backs of the preceding four teeth, and as a result thereof the conveyor 102 is allowed to advance over a correspondingly larger distance which is effective to move the completely filled filler fully out from underneath the egg distributing conveyor onto a suitable ramp 536 (FIG. 1), while moving a directly succeeding filler with its leading pocket row into egg receiving position underneath said egg supply conveyor. Another cycle in the operation of the egg packing machine has commenced. Since the stack separating and filler dispensing mechanisms of the magazine 104 are powered from the conveyor drive shaft 112, as previously explained, the intermittent rotation of said shaft 112 as controlled by the memory device 105 may readily be arranged to actuate the stack separating and filler dispensing mechanisms at the proper rate to insure that fillers are delivered to the filler supply conveyor 102 in an uninterrupted procession.

While I have described my invention with the aid of a particular embodiment thereof, it will be understood that the invention is not limited to the specific constructional details illustrated and described which may be departed from without departing from the scope and spirit of the invention.

Also while the machine of the invention as illustrated in the accompanying drawings and as described in the specification was specifically devised, and is employed, for packing eggs, it will be understood that a machine embodying the principles of the invention may also be usefully employed to pack other articles, such as avocados, lemons, or other highly priced fruit.

I claim:

1. In a filler magazine having elements defining a space adapted to receive a stack of vertically superposed fillers, a filler separating mechanism comprising filler supporting lugs, means mounting said lugs for movement from a position wherein they project into the magazine space to support a stack of fillers in said magazine to a position wherein they are retracted from the magazine space, downwardly directed spring fingers arranged

to yield outwardly to permit fillers to pass in a downward direction into engagement with said lugs and pressing inwardly with their free ends a limited distance above said lugs to positively block return of a filler once it has passed them in downward direction, rotary elements at opposite sides of said magazine at a level above the level of said lugs periodically effective to lift a stack of fillers resting upon said lugs to a higher level and thus detach fillers below the level of said spring fingers from the stack, a power driven spindle connected in driving engagement with each rotary element, and a retractor member carried by each spindle for movement in a circular path into engagement with said lug mounting means to shift said lugs from supporting relation below the detached fillers as said rotary elements elevate the stack.

2. In a filler magazine having elements defining a space adapted to receive a stack of vertically superposed fillers, a filler separating mechanism comprising filler supporting lugs movable from a position wherein they project into the magazine space from opposite walls thereof to support a stack of fillers in said magazine to a position wherein they are retracted from the magazine space, downwardly directed inwardly turned spring fingers arranged to yield outwardly to permit fillers to pass them in a downward direction into engagement with said lugs, and also arranged to press inwardly with their free ends a limited distance above the level of said lugs to positively block return of a filler once it has passed them in a downward direction, rotary elements at opposite sides of said magazine at a level above the level of said lugs periodically effective to laterally engage a stack of fillers resting upon said lugs and lift it to a higher level to detach fillers below the level of said spring fingers from the stack, and means operable to retract said lugs at the time when said rotary elements lift the filler stack to allow the detached fillers to drop below the level of the lugs.

3. In a magazine adapted to receive a stack of superposed fillers, a filler dispensing mechanism comprising first supporting means movable from a position wherein it supports stack of fillers within the magazine to a position laterally retracted from said magazine, second stack supporting means movable from a position withdrawn from the stack to two consecutive stack-supporting positions below said first supporting means in stack supporting position and also movable from a position a limited distance below said first stack supporting means in stack supporting position to a substantially lower position, gripping means on said second supporting means effective to enter between the lowermost filler of a stack of fillers supported on said second supporting means and the directly superposed filler when said second supporting means is moved into the second of said two stack supporting positions thereof, and means cyclically operable to move said second supporting means into the first of its stack supporting positions below said first supporting means with said gripping means still withdrawn from the stack in the magazine, retract said first supporting means from underneath a stack supported thereon to allow the stack to drop onto said second supporting means, move said second supporting means into the second of its stack supporting positions to cause said gripping means to engage over the lowermost filler in the stack supported by said second supporting means, return said first supporting means into stack supporting position above said lowermost filler and beneath the second lowest filler in the stack, and then cause said second supporting means with said gripping means engaged over the lowermost filler to descend to said substantially lower position.

4. In a magazine adapted to receive a stack of superposed fillers, a filler dispensing mechanism comprising first supporting means movable from a position wherein it supports a stack of fillers within the magazine to a position laterally withdrawn from said magazine, second

stack supporting means movable from a position laterally withdrawn from the stack to two consecutive stack supporting positions below said first supporting means in stack supporting position and also movable from a position a distance below said first stack supporting means in stack supporting position equal to the space between two superposed fillers in the stack to a substantially lower position, gripping means on said second supporting means effective to enter between the lowermost filler of a stack of fillers supported on said second supporting means and the directly superposed filler when said second supporting means is moved into the second of said two stack supporting positions thereof, and means cyclically operable to move said second supporting means into the first of its stack supporting positions below said first supporting means with said gripping means still withdrawn from the stack in the magazine, retract said first supporting means from underneath a stack supported thereon to allow the stack to drop onto said second supporting means, move said second supporting means into the second of its stack supporting positions to cause said gripping means to engage over the lowermost filler in the stack supported by said second supporting means and underneath the second lowest filler in the stack, return said first supporting means into stack supporting position above said lowermost filler and beneath the second lowest filler in the stack, and then cause said second supporting means with said gripping means engaged over the lowermost filler to descend to said substantially lower position.

5. In a magazine adapted to receive a stack of superposed fillers, a filler dispensing mechanism comprising supporting tongues movable from positions wherein they support a stack of fillers within the magazine to positions laterally withdrawn from said magazine, stack supporting shelves movable from positions laterally withdrawn from the stack to two consecutive stack-supporting positions below said supporting tongues in stack supporting position and also movable from a position a distance below said tongues in stack supporting position equal to the space between two superposed fillers in the stack to a substantially lower position, gripping blades on said shelves effective to enter between the lowermost filler of a stack of fillers supported on said shelves and the directly superposed filler when said shelves are moved into the second of said two stack supporting positions thereof, and means cyclically operable to move said shelves into the first of their stack supporting positions below said supporting tongues wherein said gripping blades are still withdrawn from the stack in the magazine, withdraw said supporting tongues from underneath a stack supported thereon to allow the stack to drop onto said shelves, move said shelves into the second of their stack supporting positions to cause said gripping blades to slide over the lowermost filler in the stack supported by said shelves and underneath the second lowest filler in the stack, return said supporting tongues into stack supporting position above said lowermost filler and beneath the second lowest filler in the stack, and then cause said shelves with said gripping blades engaged over the lowermost filler to descend to said substantially lower position.

6. A filler supply arrangement for egg packing machines comprising a filler magazine having elements defining an open ended space adapted to receive a stack of superposed fillers through the upper end thereof, mechanism for dispensing fillers individually and positively from the lower end of the magazine including filler supporting tongues extending into said magazine and movable between a position wherein they support a filler deposited thereon and a position withdrawn from said magazine, filler gripping claws each having a filler supporting member and a filler gripping blade disposed closely above said supporting member, being of shorter length in a direction inwardly of the magazine than its associated filler

supporting member, said claws being movable from a position withdrawn from said magazine to two consecutive filler supporting positions, and being also movable vertically from a position directly below the level of said tongues in filler supporting position to a lower level, means for actuating said filler dispensing mechanism to move said claws into their first filler supporting position underneath the edges of a filler on said tongues, withdraw said tongues from underneath the filler to cause it to drop onto and be supported by the filler supporting members of said claws, move said claws deeper into the magazine into the second of their filler supporting positions to engage the gripping blades thereof over the edges of the filler, return said tongues to their filler supporting positions above the filler to separate it from fillers thereabove, thereafter moving said claws to said lower level with the filler engaged underneath their gripping blades, and to withdraw said claws from the magazine and thus release said filler and deposit the filler.
